MARTIN NYSTROM, OF CHICAGO, ILLINOIS, ASSIGNOR, BY MESNE ASSIGNMENTS, TO
UNITED RESEARCH CORPORATION, OF LONG ISLAND CITY, NEW YORK, A CORPORA-
TION OF DELAWARE

SOUND REPRODUCING DEVICE

Application filed April 10, 1926. Serial No. 101,185.

My invention relates to devices for reproducing sound and it has a special relation to sound boxes for phonographs.

One object of the invention is to provide an extremely thin and light diaphragm which is readily flexible at an outer portion but rigid at the center so as to exert a piston-like action whereby especial sensitiveness will be assured and the reproduction will be rendered faithful over a wide range of frequencies.

Another object of the invention is to provide an extremely thin and therefore sensitive diaphragm with central reinforcing pieces engaging the same at the center for preventing central flexure and undesirable vibrations which accompany such flexure.

A further object of the invention is to provide a thin diaphragm having light reinforcing pieces on opposite sides of its central portion with deformations for preventing flexure of the central portion.

A still further object of the invention is to provide light and durable means for clamping reinforcing pieces to the center of a diaphragm and securing the diaphragm to a vibratory member for actuating the diaphragm.

Other objects and advantages of the invention will appear as the description proceeds.

In the accompanying drawings

Fig. 1 is a central sectional view on a large scale of a sound box, illustrating the invention.

Fig. 2 is a side elevational view of the sound box shown in Fig. 1, a portion of a guard being broken away to disclose parts enclosed thereby, and Fig. 3 is a detail side elevational view of the diaphragm, parts thereof being broken away.

In order that the diaphragm 1 may be very sensitive it is made of minimum mass and is extremely thin. It may be approximately .002" in thickness, and composed of a light metal such as aluminum or an aluminum alloy. The outer portion of the diaphragm is flexible and to facilitate flexure, may be provided with annular corrugations 50 2 of suitable number.

An annular deformation 3 may be provided for making the center of the diaphragm rigid and it may be so formed that its sides and substantially trunco conical in shape. Interiorly of the deformation 3 the diaphragm 55 may be formed into a cone 4 and is therefore rendered inflexible throughout this area.

The center of the diaphragm may be further strengthened by a pair of reinforcing pieces 5 and 6 which may fit snugly against 60 its opposite faces, and which may conform closely to the shape of the cone 4 and the deformation 3. The reinforcing pieces may be provided with deformations 7 and 8, similar to the deformation 3, and are of very low 65 mass. They may be composed of a light metal such as aluminum or an aluminum alloy and may be approximately .002" in thickness.

Radial indentations may also be provided 70 for further stiffening the reinforcing pieces and the diaphragm. Indentations 9 in the reinforcing piece 6 may be superimposed on and nest in similar indentations 9¹ in the cone 4 and those in the cone may be superimposed 75 on and nest in similar indentations 9¹¹ in the reinforcing piece 5. The rigidity of the center is such that in its vibratory movement it acts as a piston the tendency to flex and set up undesirable vibrations being eliminated.

For securing the stylus bar 10 to the diaphragm 1, the apex of the cone 4 and the adjacent portions of the reinforcing pieces 5 and 6 may be provided with registering apertures to receive the shank 11 of a rivet which 80 may be provided with a head 12 for engaging the reinforcing piece 5. The rivet may be composed of a light metal such as aluminum or an aluminum alloy and may clamp a ring 13 of suitable metal such as brass against the 85 reinforcing piece 6. The portions between the rivet head 12 and the ring 13 may be slightly flattened so as to be securely gripped. The ring 13 may be countersunk at 14 to permit the rivet to be spread therein.

The stylus bar 10 may be made of suitable material such as steel and may be rigidly secured to the ring 13 by solder 15. The stylus bar may 1 dished at 16 to provide room for the spre² end of the rivet, and may have 100

flattened terminals 17 seating snugly against the ring 13.

Such a diaphragm embodying the invention, is extremely sensitive because of the exceedingly small mass of both the central and outer portions and the readily flexible character of the exterior portion. It therefore, effects the faithful reproduction of sound over a wide range of frequencies without tendency to distortion or the setting up of undesirable vibrations.

Yet, notwithstanding its extreme sensitivity, it is very durable and shows no tendency to deteriorate even after long usage. The central portion of the diaphragm does not tend to collapse, but retains its shape permanently, and its rigidity enables it to vibrate in operation with a piston like action.

It will be apparent that the described means for securing the stylus bar to the diaphragm will have a minimum weight as the parts are small and of minimum mass. The sensitivity of the diaphragm and its readiness to respond to the impulses of the stylus bar are greatly enhanced yet at the same time the stylus bar is secured rigidly to the diaphragm in such a manner that there is no possibility of the stylus bar tearing loose.

The stylus bar 10 may be mounted for pivotal movement in any desired manner and stops 18 and 19 may be provided for limiting this movement and preventing accidental deformation of the diaphragm.

The outer portion of the diaphragm 1 is flat and may be held between a pair of washers 20, which may be pressed between a cap 21 and a plate 22. A clamping ring 23 in threaded engagement with the cap 21 may be provided for holding the latter securely in position. The face of the plate 22 is spaced slightly from the diaphragm to provide a shallow air chamber and may be provided with an annular recess 24 adjacent the edge of the reinforcing piece 5 to permit the diaphragm 1 to move toward the plate 22. The plate 22 may also have an annular rib 25 adjacent the deformation 7 which will permit movement of the diaphragm but reduce the volume of the air chamber so that it may be made quite small. The inner face of the rib 25 may converge into a throat 26.

The invention is not limited to the embodiment illustrated and described, which may be modified extensively within the spirit of the invention and a substantial range of equivalents is contemplated within the scope of the appended claims.

I claim:

1. A thin diaphragm having a conical center surrounded by an annular deformation the walls of which are oppositely inclined and a relatively narrow outer portion deformed to facilitate flexure thereof and permit the center to move as a piston.
2. An acoustic diaphragm approximately .002" in thickness, composed of an extremely light metal and having a conical center surrounded by an annular deformation, the walls of which are oppositely inclined and a relatively narrow outer portion deformed to facilitate flexure and permit piston-like movement of the center.

3. The combination of a thin diaphragm having a flexible outer portion and a pair of reinforcing members lying along opposite faces of the center of said diaphragm, said reinforcing members and said diaphragm having superimposed, annularly spaced, radial deformations for preventing flexure of the center of said diaphragm.

4. The combination with an extremely thin diaphragm having a flexible outer portion and a rigid center of the shape of a cone, of a pair of reinforcing members secured to said diaphragm and lying along opposite faces of said cone, said diaphragm and said members having similar superimposed, annularly spaced, radial deformations for preventing flexure of the center of said diaphragm.

5. The combination of a diaphragm having a flexible outer portion and a rigid substantially cone shaped center, and a pair of reinforcing members secured to said diaphragm and lying along opposite faces of said center, said diaphragm and said members having similar superimposed, annularly spaced, radial deformations for preventing flexure of the center of said diaphragm, said members and said diaphragm being composed of an extremely light metal and being extremely thin.

Signed at Chicago, State of Ill., United States of America, this 9 day of April A. D., 1926.

MARTIN NYSTROM.
